UNITED STATES PATENT OFFICE.

CHARLES TABER, OF PHALANX, NEW JERSEY.

COLLAPSIBLE BOX.

1,224,234.

Specification of Letters Patent.

Patented May 1, 1917.

Application filed April 5, 1916. Serial No. 89,116.

To all whom it may concern:

Be it known that I, CHARLES TABER, a citizen of the United States, residing in Phalanx, Monmouth county, New Jersey, have invented certain new and useful Improvements in Collapsible Boxes, of which the following is a specification.

The invention aims to provide a box which can be conveniently used for shipping articles or a number of separate packages and which can then be collapsed into a small space and returned to the original shipper. Such boxes have a wide variety of uses. My improved box has a number 15 of features of advantage, referred to in detail hereinafter.

The accompanying drawings illustrate embodiments of the invention.

Figure 1 is a perspective view of the box 20 assembled ready for shipment;

Fig. 2 is a similar view with the top and one side and one end removed so as to show the interior;

Fig. 3 is a sectional view of a portion of 25 the top or bottom;

Fig. 4 is a side elevation and Fig. 5 an end elevation showing the box collapsed and its parts nested for shipment in compact form;

Fig. 6 is a longitudinal section of one end 30 of the members nested and Fig. 7 is a cross-section of one side thereof;

Fig. 8 is a perspective view of a corner 35 of the box illustrating a modified construction;

Fig. 9 is a section showing the manner of nesting the parts when modified as in Fig. 8.

Figs. 10 and 11 are a plan and perspective illustrating a partitioning system;

Fig. 12 is a view similar to Fig. 2 and 40 Figs. 13 and 14 are views similar to Figs. 6 and 7 illustrating a modified construction.

Referring now to the embodiments of the invention illustrated, the box is of rectangular shape comprising a top A and bottom A', sides B and B' and ends C and C'. The opposite members are identical with each other, or substantially so.

The bottom comprises a central plate with 50 flanges D and E on its four edges and projecting outward in the assembled position of the parts. The side plates B extend perpendicularly to the bottom and top and are reinforced on their top and bottom edges.

55 Preferably they are provided with bottom and top flanges F and G parallel with the

bottom and top plates so as not only to reinforce the edges but also to facilitate nesting as hereinafter described. The ends have also bottom and top flanges H and J. The 60 bottom and top of the box have supplementary flanges K and L substantially parallel with the central plate portions thereof, which supplementary flanges are engaged by the top and bottom flanges of the sides 65 and ends. The flanges K and L of the bottom and top are reinforced at their outer edge beyond the flanges of the sides and ends, the reinforcement comprising, as shown in Fig. 3, a flat wire M extending 70 continuously around the four flanges, the edges of the supplementary flanges being bent around to inclose such wire. The sides have inwardly projecting flanges N on their vertical edges where they meet the ends, 75 which flanges stiffen the side plates in the vertical direction and provide a wide bearing to engage the ends. The ends have similar inwardly extending flanges O along their vertical edges, which flanges embrace 80 the adjacent edges of the sides as indicated in Fig. 1. The flanges N and O, therefore, provide a double thickness of metal along each vertical corner of the box thus giving these corners great strength. The additional protection afforded by the flanges of the top and bottom plates along the horizontal edges result in making a box of great strength, reinforced at all its corners.

The fastening means for holding the parts 90 together in assembled position are located entirely outside of the space within the box so as to leave the latter clear, and thus to facilitate the easy and compact filling of the box with the goods to be transported. As 95 illustrated, the fastening means consists of rods P which pass across the outside of the top and bottom plates, through holes Q in the flanges D thereof, through holes R (Fig. 2) in the upper and lower portions of the 100 side plates and through similar holes S in the overlapping vertical flanges O of the end plates. Each of the rods P has a bent end long enough to strike against the projecting horizontal flange K of the top or 105 bottom plate to prevent rotation of the rod, and has its opposite end screw threaded to receive a fastening nut T, which may be a wing nut in case of boxes of large size, or may be knurled on its edge to facilitate 110 turning it by hand. The end of the rod P beyond the nut T when the latter is screwed

home is formed with a transverse aperture to receive a lock or the wire of a seal U to prevent the box from being opened in transit. Two such rods P are used at the top and two at the bottom, fastening the parts together firmly and rigidly. They are easily applied and the nuts screwed thereon, without entering the box. As indicated in Fig. 2 there will be a clear rectangular space within the box so that the ordinary rectangular packages can be fitted closely therein.

To assemble the box the sides are placed in position on the supplementary flange of the bottom, the end flanges N of the sides embracing the ends of the bottom and the bottom flanges F of the sides resting on the supplementary flanges K of the bottom. The ends are then set up with their bottom flanges H resting on the supplementary flanges L of the bottom, and with their vertical flanges O embracing the vertical edges of the side plates. The rods P are then inserted through the bottom and through the lower portions of the sides and ends, thus fastening the box together with its top open for packing. In such packing operation the operator will come in contact only with the comparatively smooth bent edges G' and J' constituting the bases of the top flanges G and J of the sides and ends so that there is less liability of injury than if an edge of the metal were exposed at these points. For ease of handling, the end plates C, C' may be provided with handles such as V located at any suitable height. Smaller boxes may be made without handles. When the box is filled the top A is applied as shown in Fig. 1, embraced on its ends and sides by the end and side members and with its flanges K and L bearing on and protecting the top flanges of the side and end members. The rods P are then inserted and fastened as described. Instead of nuts the rods may be held by any sort of snap catches which permit the rod to be passed through the holes but prevent its withdrawal, the catch being locked or sealed during transportation.

When the box is to be shipped empty it is collapsed in the manner indicated in Figs. 4 to 7. On the bottom plate A' is placed one of the side plates as B', the height of the side plates being such that the space between its top and bottom flanges F and G is just greater than the width of the top and bottom plates so that the latter may be nested compactly within such flanges as indicated in Figs. 5 and 7. On the side plate B' is placed one of the end plates, as C', the width of the end plates between their vertical flanges being just greater than the height of the side plates so that the latter may be nested compactly within said flanges O of the end plates. On top of the end plate C' is placed the end plate C with the

top and bottom flanges of said plates overlapping one another as indicated at J, Fig. 6. Within the side flanges O of the end plate C is nested the side plate B; and between the top and bottom flanges F and G of the latter is nested the top plate A. The plates B and B' have their vertical flanges N extending inward and overlapped as in Fig. 6. Thus in the collapsed arrangement the members occupy a space equal in length and breadth to that of the assembled box and equal in thickness to three times the width of the several flanges O, G and D (plus the thickness of the central plates of the several members which is very trifling). The only exposed edges are the reinforced flanged edges of the top and bottom plates so that there is very little liability to serious injury. The parts are made up of plain surfaces, so that in case of an extraordinary blow and the bending of any of the parts they can easily be straightened with a hammer sufficiently for further use; and this applies, of course, to injuries received either in the assembled box or in the collapsed arrangement.

In previously known collapsible boxes there is apt to be a loss of the comparatively small fastening members where these are used only in fastening the assembled box. A feature of improvement in my invention is the utilization of the same fastening means for fastening the parts together in the collapsing arrangement. The manner of fastening the parts together in the nested position illustrated is as follows: First, the two end plates are arranged as shown and two of the rods P are passed through holes W (Figs. 2 and 6) formed for this purpose in the top and bottom flanges, the rods passing clear through the opposite flanges. The nuts are screwed lightly on the ends of the rods to hold the parts together. A bottom and side plate as B' and A' are then nested in the position shown and the two united end plates are placed thereon and fastened thereto by one of the rods P passing through openings provided in the center of the vertical flanges O of the ends, in the center of the top and bottom flanges F and G of the sides and in the side flanges D of the bottom and top such openings being indicated at Q', Q² and Q³, Fig. 2. This rod P also passes clear through both sets of flanges at opposite sides of the assemblage and is fastened lightly by its nut. The top and the remaining side are then similarly assembled and inverted and nested within the upwardly projecting side flanges O of the uppermost end piece, as illustrated, and the remaining fastening rod and nut are used in a similar way to fasten this top and side and end piece together.

Thus the collapsed and nested parts constitute two bundles, each consisting of a

bottom (or top) a side and an end nested within one another. Since the two opposite sides do not have to nest within one another, nor the bottom and top, nor the two opposite ends, these opposite members of the box 5 may be made identical in size so as to produce a box which is perfectly rectangular and, therefore, of the most convenient size and of the greatest capacity for most classes of goods.

10 For boxes of larger size for carrying heavier loads two additional fastening rods may be used, one at the top and one at the bottom, parallel with the rod P in Fig. 1, 15 such a rod being shown in dotted lines at P' passing through the hole Q³ in the flange of the top plate and passing through the side plates in the same way as the rod P. In this case, besides the two rods used to 20 fasten the two end plates C and C' together, there will be also used for nesting the parts two rods fastening each of the vertical flanges O of the end plates to the nested side and bottom (or top) plates instead of the 25 one rod previously described; thus using the entire six rods which are used to hold the box in assembled position. Such rods for example can pass in the collapsed position of the parts through the holes S of the vertical flanges O of the end members and 30 through correspondingly located holes in the top and bottom flanges G and H of the side plates and in the side flanges D of the bottom and top members.

35 Ordinarily in assembling and packing the box the mounting and fastening of the sides and ends on the bottom will hold them sufficiently rigidly to permit packing. Or the top rods P may be inserted to hold them 40 temporarily together. But additional means may be used for holding them together more stiffly in this position even while the box is open. Such a means is indicated in Figs. 8 and 9 and comprises buttons X on the outer 45 faces of the vertical flanges N of the side plates, as B. The end plates, as C are pro-

vided with openings Y tapered in width, adapted to pass said buttons X at one end, but to engage the shank of the same and to 50 prevent withdrawal of the button at the other end. The upper flange G of the plate B is cut away at its end so as to permit a relative vertical movement of the vertical flange O of the end member C in assembling the box. The end member is then

brought up to the side members in an elevated position so that the buttons X pass through the lower ends of the openings Y, and is shoved downward until the buttons 55 are caught in the upper ends of such openings. The sides and ends should first be assembled in this way and the top then placed on and fastened by its rods, after which the box should be inverted so that the 60 part which was the top now becomes the bot-

tom, and the top is open. For greater compactness and to hold the parts together better in the nested position the flanges N of the side members B, B', may be notched as indicated at Z and the buttons X of one such 70 member staggered relatively to those of the other so that the buttons of the member B, for example, as shown in Fig. 9, may be caught in the notches Z of the flange of the opposite member.

75 The space between the end members as nested illustrated best in Figs. 6 and 7, will accommodate the handles, where handles are used. It is also sufficient to accommodate other things such, for example, as removable 80 partitions or other fittings that can be set within the box for carrying certain articles. For example, collapsible partitions like those shown in Figs. 10 and 11 may be used for packing the box. These consist of strips a 85 and b notched into each other to form separate compartments and adapted to be either taken apart or to be flattened together in a well known manner. When a partitioning device of this character is flattened it increases in length like a lazy-tongs. In order that such partitions in flattened condition shall fit within the space between the ends of the nested parts it must not be wider than the box. To secure this result I propose to 90 divide the space, as indicated for example in Fig. 10, into a number of equal sections, each of less width than the box and to fill it with separate crates or collapsible partitioning devices indicated as a whole at c; the spaces 100 between the collapsible devices being provided with separately removable partitions d and e. Thus the interior partitions within the box are all adapted to be knocked down or collapsed sufficiently to bring them 105 within a space equal to the width of the box (and, of course, they are no greater in height than the ends of the box) so that they can be fitted within the space between the 110 nested ends.

Where the reinforcement of the top and bottom edges of the side plates is in the form of a right-angled flange as in Fig. 2 the sides must be of such height that their top and bottom flanges F and G can embrace 115 the flanges D of the top and bottom members of the box. For this result, therefore, the height of the box must be as great as its width. These flanges are not essential in all cases, however, and in Figs. 12, 13 and 120 14 I have illustrated a box of less height in comparison to its width. Here the bottom and end pieces are identical with those shown in Fig. 2, but the side pieces B, B' lack the top and bottom flanges G and F of Fig. 2. Any other suitable reinforcing may be used or they may be without reinforcement, as illustrated. When this box is set up the edges of the sides are protected from 125 injury by the flanges of the top and bottom, 130

members. Also the top and bottom edges of the sides are capable of resisting inward pressure by their bearing against the flanges D of the top and bottom members. But for greater resistance against the outward thrust of the contents of the box a third fastening rod P should be used both at the top and at the bottom, passing through holes Q¹ (Fig. 12) near the top and bottom edges 10 of the side members. This provides six fastening rods, all of which will be used to fasten the parts together when nested, by forming suitable holes in the flanges as previously described.

15 The nesting of boxes constructed in this way is indicated in Figs. 13 and 14. It is the same as for the previously described construction except that the end flanges N of the side members B and B' are turned outward to overlap the flanges E of the top and bottom members instead of being turned inward toward each other. The side members are held by this overlapping of their end flanges against any skewing movement and 20 they are held against escape by their location between the bottom and top members or between the side and top members respectively which overlap as at D and O in Fig. 14 and thus inclose and prevent the loss of 25 the side members.

30 The opposite members of my improved box are identical and are reversible endwise so that the assembling of them in setting up the box and the nesting of them in the collapsed position requires the least possible care and time. The fastening means are on the outside and yet are abundantly protected by the overhanging flanges. There is little or no chance of the fastening means being 35 lost when the box is returned, since these fastening means are used to assemble the parts in the collapsed position.

35 Instead of making the members of the box of sheet metal, with integral flanges bent up therefrom they, or any of them, may be made of separate angles mounted on plates of thinner material, either metal, wood or fiber board. For example, the top and bottom or the top alone may be made of aluminum 40 angles with stiff pasteboard centers, the sides and ends, and perhaps the bottom, being made wholly of aluminum or sheet steel pressed into shape. The proportions of the box may be varied within a considerable 45 range, it may be sold commercially as an open box, to be covered in any manner desired by the purchaser, or to be always open in certain uses. A round box may be made on substantially the same principle, by using 50 a round bottom or end plate, and various other shapes and proportions may be used so that the terms "sides" "ends" "top" and "bottom" are generally interchangeable.

55 What I claim is—

60 1. A collapsible box comprising side mem-

bers having reinforced top edges, and adapted to be assembled into a box with an opening equal to the full width and length of the box and a top member fitting within the upper portions of said side members 70 and having on its edges outwardly projecting flanges substantially parallel with said side members, and a bottom member, said members being adapted also to be collapsed into a compact arrangement. 75

2. A collapsible box comprising side members adapted to be assembled into a box with an opening at the top equal to the full width and length of the box, a top member fitting within the upper portions of said 80 side members and having on its edges outwardly projecting flanges substantially parallel with said side members and having additional flanges substantially parallel with said top member and overlying the top 85 of said side members, and a bottom member, said side and top and bottom members being adapted also to be collapsed into a compact arrangement.

3. A collapsible box comprising a plate 90 with outside flanges on its edges and other plates perpendicular thereto and fitting outside of said flanges in the assembled position, and having flanges substantially parallel with said first plate, said first plate having supplementary flanges parallel to the plate and engaged by the flanges on said other plates, said supplementary flanges having a reinforced outer edge beyond the flanges of said other members. 95

4. A collapsible box comprising three pairs of flanged members adapted to be assembled to form a box with the members of each pair opposite each other and of identical size to each other so as to form a perfectly rectangular box, said members adapted to be collapsed and nested one within the flanges of another in two bundles, each bundle comprising one of each of said pairs. 105

5. A collapsible box comprising three 110 pairs of flanged members adapted to be assembled to form a box with the members of each pair opposite each other and of identical size with each other so as to form a perfectly rectangular box, said members adapted to be collapsed and nested one within the flanges of another in two bundles, each bundle comprising one of each said pairs, and means adapted to fasten said members together either in the assembled or the collapsed arrangement. 115

6. A collapsible box comprising three pairs of flanged members adapted to be assembled to form a box with the members of each pair opposite each other and of identical size with each other so as to form a perfectly rectangular box, said members adapted to be collapsed and nested one within the flanges of another in two bundles, each bundle comprising one of each 120

125

of said pairs, and means adapted to fasten said members together either in the assembled or the collapsed arrangement and also to fasten said two bundles to each other.

5 7. A collapsible box comprising side members adapted to be assembled into a box with an opening at the top equal to the full width and length of the box, a top member fitting within the upper portions of 10 said side members and having on its edges outwardly projecting flanges substantially parallel with said side members, and a bottom member, said side members and top and bottom members being adapted also to 15 be collapsed into a compact arrangement, and fastening means consisting of rods adapted in the assembled position of the parts to extend across the outside of said top member and through 20 and the adjacent portions of the side members.

8. A collapsible box comprising side members adapted to be assembled into a box with an opening at the top equal to the full width and length of the box, a top member fitting 25 within the upper portions of said side members and having on its edges outwardly projecting flanges substantially parallel with said side members, and a bottom member, said side members and top and bottom mem- 30 bers being adapted also to be collapsed into a compact arrangement, and fastening means consisting of rods adapted in the assembled position of the parts to extend across the outside of said top member and through 35 the flanges thereof and the adjacent portions of the side members, said members adapted also to be fastened together in the collapsed arrangement of said rods.

In witness whereof, I have hereunto 40 signed my name.

CHARLES TABER.
